[57] CLAIM

The ornamental design for a ladder platform, as shown and described.

DESCRIPTION

FIG. 1 is a perspective view of a ladder platform showing our new design, it being understood that the broken line showing of the ladder is for illustrative purposes only;

FIG. 2 is a perspective view thereof shown in an alternate position;

FIG. 3 is an enlarged top plan view thereof in folded condition;

FIG. 4 is a rear elevational view of FIG. 3;

FIG. 5 is a side elevational view of FIG. 3; and

FIG. 6 is a bottom plan view of FIG. 3.

FIG. 4

FIG. 5

FIG. 6
